CLAIM

The ornamental design for combined horizontal wall
mount and vertical standard, as shown and described.

DESCRIPTION

FIG. 1 is a top, front, and left side perspective view of
a combined horizontal wall mount and vertical standard
showing my new design;

FIG. 2 is a left side elevational view thereof, the right
side being a mirror image of that shown;

FIG. 3 is a rear elevational view thereof;

FIG. 4 is a top plan view thereof;

FIG. 5 is a front elevational view thereof;

FIG. 6 is a top front and left side perspective view of
the vertical standard portion thereof, the horizontal
wall mount portion being omitted for clarity of illustration;

FIG. 7 is a front elevational view of the vertical stan-
dard portion thereof;

FIG. 8 is a rear elevational view of the vertical standard
portion thereof;

FIG. 9 is a left side elevational view of the vertical
standard portion thereof, the right side being a mirror
image of that shown;

FIG. 10 is a top plan view of the vertical standard portion
thereof, the bottom being identical in appearance;

FIG. 11 is a top, front, and left side perspective view of

the wall mount portion thereof;

FIG. 12 is a front elevational view of the wall mount
portion thereof;

FIG. 13 is a rear elevational view of the wall mount
portion thereof;

FIG. 14 is a top plan view of the wall mount portion
thereof; and,

FIG. 15 is a left side elevational view of the wall mount
portion thereof, the right side being identical in appear-
ance.
